DRIVING MECHANISM FOR SLICING MACHINES

Franciscus L. van Weenen, Rotterdam, Netherlands, assignor to U. S. Slicing Machine Company, La Porte, Ind., a corporation of Indiana

Application November 14, 1929, Serial No. 407,268,
and in Great Britain November 21, 1928

26 Claims. (Cl. 146—102)

This invention relates to machines of the type in which there is a rotating slicing knife and a carriage which reciprocates past the slicing knife so that a substance supported on the carriage may have successive slices cut therefrom by the knife as the substance is recurrently moved past the slicing knife. The substance to be sliced is fed with a step by step movement in a direction toward the cutting plane of the knife.

10 One object of the present invention is to provide a drive for such a slicing machine which will permit driving the knife and carriage in unison by power or by manual means and also for operating either the carriage or knife by power or for 15 operating the carriage only by manual means. Also, it is possible to drive one of the parts by hand and the other by power. Such an arrangement is desirable when it is desired to use the machine for slicing a variety of substances.

20 Another object of this invention is the provision of mechanism for accomplishing the above-noted results and which mechanism readily enables one to change from one mode of operation to another.

Another object of this invention is the provision 25 of one or more double-acting clutch devices interposed between the power drive and the manual drive for the slicing machine.

Still another object of this invention is the provision of suitable operating mechanism for each 30 clutch device used.

Other objects of the invention will appear as the description proceeds.

In the drawings:—

Fig. 1 represents a side elevation of a device embodying my invention with the cover plate over 35 part of the driving mechanism removed;

Fig. 2 is a section substantially on the line 2—2 of Fig. 1;

Fig. 3 is a cross section on an enlarged scale of 40 certain of the parts shown in Fig. 2;

Fig. 4 is a cross section on the line 4—4 of Fig. 3;

Fig. 5 is a cross section on the line 5—5 of Fig. 3; and

Fig. 6 is a detail of the mounting for the pulley 45 which is driven directly from the motor.

Referring more particularly to Fig. 1, it will be noted that the slicing machine comprises a base 1 having guide rods 2 supported on suitable brackets such as 3, as in the ordinary construction of 50 such slicing machines. A carriage 4 is adapted to be supported and guided by the guide rods 2 as the carriage is moved therealong. The carriage is reciprocated along the guide rods 2 by means of the rotating crank 5 and connecting rod 6, the latter being pivotally connected to the crank and

to the carriage in the usual manner. The crank 5 is rigidly connected to a short shaft 7 journaled in the frame 1, said shaft carrying a bevel gear 8 at its lower end. This bevel gear 8 meshes with a similar bevel gear 9 mounted on a shaft 10 which 60 extends longitudinally of the base of the machine. A fly-wheel 11 having a handle 12 for rotating the same is rigidly mounted on the shaft 10 and rotation of the fly-wheel 11 causes the carriage 4 to reciprocate through the gears 8 and 9, crank 65 5 and connecting rod 6. The features of the device so far described are all old and well known.

Rigidly secured to the base member 1 is a bracket 13 which rotatably supports the shaft 14 carrying the knife 15. The shaft 14 carries a sprocket 70 16 over which is trained the chain 17, the latter being used to drive the sprocket when actuated by mechanism which I will now proceed to describe.

Referring more particularly to Figs. 1, 2 and 3, 75 it will be noted that the bracket 13 also supports a hollow drive shaft 18 having a longitudinal bore 19 for a purpose which will appear later. Suitable anti-friction bearings 20 and 21 are interposed between the bearing 22 of the bracket 3 and the 80 hollow rotatable shaft 18. The hollow rotatable shaft 18 is adapted to support the sprockets 23 and 24, respectively, the former being connected by means of the chain 25 to a gear 26 mounted on a shaft 27 driven by means of a bevel gear 28 85 from the bevel gear 8 on the shaft 7. A sprocket 48 freely rotatable on a stud 49 engages the chain 25 and acts as a belt tightener therefor, the stud 49 being adjustable in the longitudinal slot 50 in the bracket 13. The sprocket 24 also has the 90 chain 17 trained thereover and this chain is also trained over the sprocket 29 freely rotatable on a supporting stud 30, said stud being adjustable in the longitudinal slot 31 in the bracket 13 so that the sprocket 29 acts as a tensioning means for the 95 chain 17. In other words, the chain 17 is trained over the sprockets 16, 23 and 29, the latter being adjustable to impart a suitable tension to the chain 17.

The hollow shaft 18 also rotatably supports a 100 pulley 32 and this pulley is adapted to be driven by means of a motor 33 having a pulley 34 thereon, through the intermediary of the belt 35 trained over the pulleys 34 and 32. An arm 36 pivoted at 37 carries a roller 38 at its free end and this roller is yieldingly urged into engagement with a run of the belt 35 by means of a spring 39 connected to the arm 36 intermediate its ends and to the bracket 13 at 40. The arm 36 acts as a 105 belt tightener for the belt 35.

The motor 33 acts as a power means for driving the carriage and the knife, or either one separately, and the handle 12 is the manual means used for selectively driving the knife and carriage, 5 or the carriage only, as may be desired. However, if the sprockets 23 and 24 and the pulley 32 were rigidly connected to the hollow shaft 18, it would only be possible to drive the carriage and knife in unison and, when the manual means was being 10 used, it would be necessary to drive the motor as well as the carriage and the knife unless means were provided for preventing this. In the device illustrated in the drawings, however, applicant has disclosed a means for rendering the power 15 driving means inoperative when the manual means is being used to drive either the carriage, or both the carriage and the knife, and means has also been provided for permitting the manual means and power means to selectively operate either the 20 carriage or the knife, or both, as the case may be. This result has been accomplished by means of suitable clutch devices interposed between each of the sprockets 23 and 24 and the hollow shaft 18, and also by providing a suitable one-way 25 clutch device between the pulley 32 and the hollow shaft 18.

As will be more clearly seen in Fig. 6, the pulley 32 is rotatable on a hub portion 41 keyed to the hollow shaft 18 by means of a key 42. The hub portion 41 has a plurality of recesses 43 therein, each of which has a cam surface 44, and a roller 45 is interposed between the cam surface 44 and the adjacent surface of the pulley 32. Each of the rollers 45 is urged in a clockwise direction by means of a spring 46 bearing against the hub portion 41 adjacent one end of the recess 43 and the bottom of a recess in a suitable abutment member 47 which engages the roller 45. It will be noted from an inspection of Fig. 6 that, when 40 the pulley 32 is rotated in a clockwise direction, the rollers 45 are rotated in a clockwise direction due to their engagement with the pulley 32 and this has a tendency to roll the rollers 45 over the cam surface 44 towards the end of the recess 45 43 away from the spring 46. Since this end of the recess 43 is of less width than the diameter of the roller 45, the roller is wedged in between the cam surface 44 and the pulley 32, thus causing the hub portion 41 to be carried in a clockwise 50 direction along with the pulley 32 as the latter is rotated. However, it will be noted that if the hub portion 41 is rotated instead of the pulley 32, the latter will remain stationary since the rollers 45 will then be rotated in a counter-clockwise direction so as to tend to move said rollers into the larger portion of the recess 43. The advantages of this construction will appear later.

The mountings for the sprocket 24 and the sprocket 23 are identical but will be referred to by different reference numerals in order that there will be no confusion in the description. Referring now to Fig. 4, it will be noted that the sprocket 24 is rotatably mounted on a hub portion 51 which is keyed to the hollow shaft 18 by a suitable key 52. The hub portion 51 has a plurality of recesses 53 and 54 adapted to receive the pins 55. The pin 55 in the recess 53 is surrounded by a spring 56 which abuts against the enlarged conical head 57 on the pin 70 and one end 58 of the recess 53. The pin 55 in the recess 54 also has an enlarged conical head 57 and a spring 56 which surrounds the pin and is interposed between the enlarged conical head 57 and a removable abutment 59 held 75 in place within the recess by means of a suitable

pin 60 (Fig. 3) or by any other suitable fastening means. It will be noted that the springs 56 normally urge the pins 55 toward the center of the hub portion 51. Each of the pins 55 is provided with a conical point 61 at its outer end. In Fig. 4, the pins are shown in their extended position. In this position, the pins extend into the recesses 62 formed in the outer periphery of the hub portion 51. Each of the recesses 62 has a cam surface 63 such as to make the recess 62 smaller at one end than at the other. Each of the recesses 62 has a roller 64 therein which extends substantially the entire width of the hub portion, as best illustrated in Fig. 3. This roller 64 is normally urged toward the smaller end of the recess 62 by means of the spring-pressed abutment 65 which has a spring 66 fitted within a recess 67 of the abutment member and abutting against one end of the recess 62. It will be noted that the pins 55 when in extended position, as shown in Fig. 4, move the rollers 64 toward the larger ends of the recesses 62 against the action of the springs 66 so as to render the rollers 64 inoperative for the purposes which will presently appear.

The hub portion 51 is also provided with a plurality of recesses 68 similar to the recesses 62 but having their smaller ends extending in a direction opposite to the direction in which the smaller ends of the recesses 62 extend. Each of these recesses 68 is also provided with rollers 69, abutments 70, springs 71 and cam surfaces 72, which are constructed in the same manner as the rollers 64, abutments 65 and springs 66. It will be noted, however, that there is no positive means for rendering the rollers 69 inoperative for a purpose which will be described later.

In Fig. 5, I have shown the construction of the hub portion for the sprocket 23 and this is identical with the construction of the hub portion of the sprocket 24 shown in Fig. 4, but in Fig. 5 I have shown the pins in retracted position instead of in extended position, as in Fig. 4. It is unnecessary to proceed with a lengthy description of Fig. 5, it only being necessary to state that the parts 51' and 53' to 72', inclusive, shown in Fig. 5, correspond with the identical parts 51 and 53 to 72, inclusive, shown in Fig. 5.

A means is provided for selectively extending or retracting the pins 55 and 55', as desired. This means comprises a rod 80 having a bearing portion 73 slidable within the recess 19 and bearing against the periphery thereof, and also has an enlarged portion 74 also acting as a bearing portion for guiding the rod 80 within the recess 19 and this enlarged portion has the oppositely inclined faces 75 and 76 and the V-shaped groove 77. The rod 80 is provided with a suitable operating knob 78 secured to one end thereof by means of the pin 79, or other suitable fastening means. In Fig. 3, the rod 80 is shown in its middle or neutral position and in this position, the pins 55 and 55' are retracted by the action of the springs 56 and 56', and the rollers 64 and 64' operate in the same manner as they would if the pins 55 and 55' were not included in the hub structure at all. However, longitudinal movement of the rod 80 to the left causes the conical portions 57' of the pins 55' to ride up over the inclined portion 75 and into the recess 77 of the enlarged portion 74. This throws the pins 55' into the position shown for the pins 55 in Fig. 4. A simi-

lar movement of the rod 80 to the right will move the pins 55 into the position shown in Fig. 4, it being understood that when the pins 55' are extended, the pins 55 are retracted and 5 vice versa.

I will now proceed to describe the operation of the device when the rod 80 is in each of its three positions of adjustment. For the purposes of description, we will refer to the middle position as the neutral position and to the other two positions of the rod 80 as the right and the left positions, the terms right and left referring to the parts as illustrated in Fig. 3.

Assume first that the rod 80 is in its neutral position. In this position, the pins 55 and 55' are retracted so that the rollers 64 and 64' occupy the positions illustrated for the rollers 64' in Fig. 5. I will consider first the action of the device when driven by means of the fly-

20 wheel 11 through the connections previously described.

By rotating the fly-wheel 11 by means of the handle 12, the sprocket 26 is caused to rotate by means of the intermeshing gears 8, 9 and 28 mounted, respectively, on the shafts 7, 10 and 27. The sprocket 26 drives the sprocket 23 by means of the chain 25 and in a clockwise direction, as viewed in Figs. 1, 4 and 5. Referring more particularly to Fig. 5, it will be noted that rotation 30 of the sprocket 23 on the hub 51' will cause the rollers 69' to rotate in a clockwise direction towards the smaller end of the recesses 68' and will cause the rollers to bind between the cam surfaces 72' and the inner bearing surface of 35 the sprocket 23, thereby causing the hub portion 51' to rotate with the sprocket 23. This also causes rotation of the hub portion 51 due to the fact that the hub portions 51 and 51' are both keyed to the hollow shaft 18. The rollers 64', 40 however, are also rotated in a clockwise direction but towards the larger ends of the recesses 62' and therefore there is no binding connection between the rollers 64' and the inner periphery of the sprocket 23, although the rollers 64' are 45 held lightly in contact therewith by means of the springs 66'.

Since the hub portion 51 is caused to rotate with the hub portion 51', there is a tendency for the cam surface 63 of the hub portion 51 to rotate the rollers 64 in a counter-clockwise direction so that the same are moved towards the smaller ends of the recesses 62, thereby causing the rollers 64 to bind against the inner bearing surface of the sprocket 24 so that the same is caused to rotate with the hub portion 51. The hub portion 51 also has a tendency to rotate the rollers 69 in a counter-clockwise direction but towards the larger ends of the recesses 68, so that while the rollers 69 are held yieldingly in 55 contact with the inner bearing surface of the sprocket 24 and the cam surface 72, there is no binding contact therewith. Since the sprocket 24 is caused to rotate with the hub 51 when the rod 80 is in its neutral position, the knife will be 60 driven by means of the chain 17 trained over the sprocket 24 and the sprocket 16, the latter being rigid with the knife spindle. The carriage 4 is also caused to reciprocate through the connections previously described in view of the fact 65 that there is always positive driving connection between the fly-wheel 11 and the carriage 4.

Assuming that the rod 80 is still in its neutral position, it will be noted that although the carriage and the knife are caused to reciprocate by 70 the manual operation of the fly-wheel 11, there

is no rotation imparted to the pulley 32 in view of the fact that while the hub 41 is caused to rotate with the shaft 18 due to the fact that it is keyed thereto, there is no positive driving connection between the hub 41 and the pulley 32 80 due to the fact that a counter clockwise rotation is imparted to the rollers 45 and this has a tendency to force the rollers 45 toward the larger ends of the recesses 43 against the action of the springs 46 so that while the rollers 45 are yieldingly held in contact with the bearing surface of the pulley 32 adjacent the outer periphery of the hub 41, there is no positive binding contact between the rollers 45 and the pulley 32 to cause the same to rotate therewith and, therefore, the pulley 32 will remain at rest, thus forming an automatic means which permits the power driving means to remain at rest whenever the hand operating means is being used.

However, it will be noted that when it is desired to drive the machine by means of the motor, motion is imparted in a clockwise direction to the pulley 32 and this moves the rollers 45 towards the smaller ends of the recesses 43, causing the same to bind against the adjacent bearing surface on the pulley 32 so that the hub 41 is caused to rotate with the pulley 32. This rotation, of course, also imparts rotation to the shaft 18 and the hub portions 51 and 51' of the sprockets 24 and 23. With the rod 80 in its neutral position 105 and with the shaft 18 power driven, motion is imparted to the sprockets 24 and 23 by means of the rollers 64 and 64', respectively, as the driving is now being done by the hub portions and whenever this is done, the rollers 64 and 64' form 110 the driving connection between the hub portions 51 and 51'. Since the sprocket 23 is positively driven, motion is imparted to the carriage 4 by means of the chain 25, sprocket 26, shaft 27, gear 28, gear 8, shaft 7, crank 5 and connecting 115 rod 6, and the knife 15 is also positively driven by means of the chain 17 trained over the sprockets 24 and 16.

From the above description, it will be seen that when the rod 80 is in its neutral position, the 120 carriage will be reciprocated and the knife will be rotated whether the machine is power driven or manually driven. This is the usual position of the rod 80 while slicing substances by means of the slicing machine described.

If, now, we assume that the rod 80 is shifted to the left, it will be noted that the rollers 64' in the hub portion 51' are rendered inoperative due to the fact that the pins 55' force the rollers 64' towards the larger ends of the recesses 62'. If, 130 now, the fly-wheel 11 is rotated, the sprocket 23 is rotated the same as before by means of the chain 25 and motion will be imparted to the hub 51' through the rollers 69' which are forced into the smaller ends of the recesses 68', the same as 135 when the rod 80 is in its neutral position. Again, the hubs 51 and 41 are caused to rotate with the hub 51' and motion is imparted to the sprocket 24 by means of the rollers 64, the same as before, and the knife is rotated, it being understood that 140 whenever the manually operated means is being used, the carriage is also reciprocated. The pulley 32 remains at rest as before.

Assuming, however, that it is desired to use the power drive when the rod 80 is in the left-hand 145 position, it will be noted that, then, the pulley 32 will drive the hub 41 and cause rotation of the hubs 51 and 51'. Rotation of the hub 51 will cause rotation of the sprocket 24 and consequently the knife 15 due to the fact that the 150

rollers 64 are forced into the smaller ends of the recesses 62. However, the rollers 64' associated with the hub portion 51', have been rendered inoperative by the pins 55' and, therefore, no motion will be imparted to the sprocket 23 due to the fact that the rollers 69' are also inoperative because the rotation of the hub 51' in a clockwise direction has the tendency to move the rollers 69' into the ends of the recesses 68'. Since the sprocket 23 is not rotated, no motion is imparted to the chain and, therefore, the carriage 4 will remain at rest or may be moved by means of the fly-wheel 11 and associated mechanism at a speed which is not greater than the speed at which the carriage would be moved if driven by the motor.

Therefore, when the rod 80 is in its left-hand position, the motor will drive only the knife, and the carriage may be moved as desired by the manual control. This permits the knife to be sharpened while being driven by the motor without the necessity of driving the carriage, and also permits the carriage to be moved to a position where the parts ground off of the knife will not fall thereon, it being undesirable to have any foreign matter deposited on the slicing machine carriage. With this arrangement, it is also possible to rotate the knife at a constant speed while the carriage is reciprocated at any desired speed, depending upon the characteristics of the substance being sliced, some substances requiring a longer draw cut than others and the most efficient slicing thereof would not be accomplished by having a carriage driven at a speed which is always proportional to the speed of the slicing knife.

Let us assume, lastly, that the rod 80 is in its right-hand position, as seen in Fig. 3. This renders the rollers 64 associated with the hub portion 51, inoperative. If, now, the manual means is used to reciprocate the carriage, the sprocket 23 will again be rotated and, in turn, will impart rotation to the hub 51' through the rollers 69' in the same manner as previously, and the hub portions 51 and 41 are also caused to rotate, the same being rigidly connected to the shaft 18. However, no motion will be imparted to the sprocket 24 from the hub portion 51 in view of the fact that the rollers 64 are inoperative to impart rotation to the sprocket 24 and the rollers 69 can not impart rotation to the sprocket 24 because a rotation of the hub 51 in a clockwise direction has a tendency to move the rollers 69 into the larger ends of the recesses 68, so that there is no positive binding contact between the rollers 69 and the sprocket 24. Since the sprocket 24 is not rotated, no motion is imparted to the knife 15. If, now, the motor is started, motion will be imparted to the hub 41 and, as a result, the hubs 51 and 51'. Again, since the rollers 64 are rendered inoperative, no motion is imparted to the sprocket 24, but motion is imparted to the sprocket 23 by means of the rollers 64' which are in operative position due to the fact that the pins 55' are retracted. Thus, the chain 25, and, as a result, the carriage 4, are positively driven. In other words, with the rod 80 in its right hand position, motion is imparted to the carriage but not to the knife by either the manual drive or the motor drive. This arrangement is particularly desirable when slicing substances such as cheese, which is more readily sliced by a knife which is free to rotate but not positively driven than by a knife which is positively driven. In other words, the material is forced against the edge of

the knife as the carriage is reciprocated and the knife presses its way through the substance and forms slices which are more uniform and neater in appearance than those cut by means of a positively driven knife.

I will now proceed to sum up the various operations which can be performed by the machine according to the position of the rod 80. By switching on the motor, (a) the carriage and the knife can be driven in unison; (b) the knife can be rotated while the carriage remains at rest, or (c) while the carriage is reciprocated by hand; and (d) the carriage can be reciprocated while the knife remains at rest. By turning the fly-wheel 11: (e) the carriage and knife can be driven in unison and (f) the carriage can be reciprocated while the knife remains at rest.

A housing 81 on the bracket 13 has a cover plate 82. This housing substantially encloses the driving connection between the motor and the shaft 18. A projection flange 83 extends outwardly from the housing 81 and substantially protects the sprockets 23, 24, 29, 48 and 26, as well as the chains 25 and 17, and also forms a means whereby the operator is protected in case either the chain 17 or the chain 25 is broken.

The slicing machine is also provided with a deflector 84 fastened by means of the screws 85 to the bracket 13. This deflector deflects the slices away from the edge of the knife and onto a suitable support adjacent the slicing machine.

It will be understood that while I have shown a particular means for driving the sprockets 23 and 24 from the hub portions 51' and 51, respectively, or for driving the hub portions by means of the respective sprockets, I do not wish to be limited to the specific means shown as any of the well known equivalents thereof can be used without departing from the spirit and scope of my invention.

The driving connection between the pulley 32 and the hub 41 may also be varied, if desired, the essential feature of the drive between the pulley 32 and the hub 41 being that motion can be imparted to the hub 41 by the pulley 32 but not to the pulley 32 by the hub 41.

Also, I wish it to be understood that my invention is capable of being used with machines of a type different than that illustrated. In other words, the invention is also applicable to slicing machines in which the carriage is pivoted, rotated or similarly mounted, and in which the knife may be moved instead of the carriage, and in which the knife may have other movements than one purely of rotation.

If desired, the fly-wheel 11 may be mounted on the shaft 10 in a manner similar to the manner in which the pulley 32 is mounted on the shaft 18. Such an arrangement will permit the fly-wheel to remain at rest while the power means is being used.

Obviously those skilled in the art may make various changes in the details and arrangement of parts without departing from the spirit and scope of the invention as defined by the claims hereto appended, and I therefore do not wish to be restricted to the precise construction herein disclosed.

Having thus fully disclosed an embodiment of my invention, what I claim and desire to secure by Letters Patent of the United States is:

1. A slicing machine comprising a slicing knife, a table adapted to reciprocate relatively thereto, manual means for rotating said knife and reciprocating said table, a clutch interposed between

- said knife and manual rotating means, a motor for driving said knife through said clutch, and means for rendering said clutch inoperative to drive said knife whether operated by said motor 5 or by said manual means.
2. A slicing machine comprising a slicing knife, a table movably mounted with respect thereto, a manual means for driving said knife and table, a clutch interposed between said knife and manual 10 driving means, a motor for driving said table through said clutch, and means for rendering said clutch inoperative to drive said table by said motor while permitting said clutch to remain operative with respect to the manual driving 15 means for said knife and said carriage.
3. A slicing machine comprising a reciprocating table, a rotatable knife, interconnected means for normally driving said table and knife in unison when motion is imparted to either one or the 20 other by a suitable driving means, a clutch included in said means for driving said table and knife in unison, said clutch comprising a plurality of elements normally caused to rotate in unison with each other by means of a plurality 25 of friction devices acting in opposite directions, a power means for operating said knife through said clutch, a manual means for operating said table and knife through said clutch, and means for rendering one of said friction devices inoperative 30 so that the drive to said knife from said power means is inoperative at the same time that the drive from said manual means to said knife is inoperative.
4. A slicing machine comprising a rotatable 35 slicing knife, a carriage adapted to reciprocate relatively thereto, manual means for driving said carriage and knife, a clutch included in said manual driving means, said clutch comprising a plurality of rotatable elements, one of which is 40 constrained to move in a definite relation to said carriage at all times, the other of which has operative connection with said knife, a pair of means interposed between said elements for operatively 45 connecting said elements in driving relation with each other, one of said last-mentioned means imparting rotation from one element to the other element when said first element is rotated in one direction, the other one of said pair of means imparting rotation from the second-mentioned 50 element to said first-mentioned element, each of said pair of means being inoperative to operatively connect said elements in driving relation with each other in a direction other than that specified, power means for actuating said carriage through 55 said clutch, and means for rendering one of said pair of means inoperative.
5. A device as claimed in claim 4 which includes a second clutch interposed between said manual driving means and said knife and means 60 for rendering said second clutch inoperative.
6. A slicing machine comprising a reciprocating carriage, a rotatable knife, two clutches interposed between said knife and said carriage for operatively connecting said knife and carriage so 65 that they will move in unison with each other, each of said clutches comprising a pair of rotatable members, friction elements interposed between said members, some of said friction elements imparting rotation from one of said members to the other of said members while others of said elements impart rotation from said second-mentioned member to said first-mentioned member, and means for selectively rendering some of said elements inoperative for the purposes specified.
7. A slicing machine comprising a reciprocating carriage, a rotatable knife, two clutches interposed between said knife and said carriage for operatively connecting said knife and carriage so that they will move in unison with each other, each of said clutches comprising a pair of rotatable members, friction elements interposed between said members, some of said friction elements imparting rotation from one of said members to the other while others of said elements impart rotation from said second-mentioned member to said first-mentioned member, and means for selectively rendering some of said elements inoperative for the purposes specified comprising a cam member and co-operating pins adapted to engage selected ones of said elements for moving said elements into inoperative position as said cam member is operated. 80
8. In a slicing machine, the combination with a carriage, of a rotating knife, mechanism for moving said knife and carriage relative to each other, mechanism for rotating said knife, power means for actuating both of said mechanisms, manual means for actuating both of said mechanisms, means for rendering the drive from said power means to either of said mechanisms, inoperative when said power means is actuated, and means for disconnecting said second mechanism from said manual means without disconnecting the mechanism connecting said manual driving 90 means and said first mechanism. 95
9. In a slicing machine, the combination with a slicing knife, of a substance support, and means for driving said knife and said support comprising a rotatable shaft, power means for actuating said shaft, a clutch mounted on said shaft having two elements rotatable relatively to each other, one of said elements being mounted to rotate with said shaft and the other of said elements being operatively connected to said carriage, a manual means for actuating said carriage and said second element, means for causing both of said elements to rotate in unison with each other, operative connections from said shaft to said knife so that said knife and carriage 110 may be both actuated by either said power means or said manual means while said elements are caused to rotate with each other, and means for rendering said elements free to move relatively to each other, so that the drive to said carriage 115 from said power means is inoperative and so that said carriage may be operated by said manual means while said knife is rotated by said power means. 120
10. A device as claimed in claim 9 in which said elements have co-operating spaced opposed surfaces between which are interposed friction elements which engage said opposed surfaces with sufficient force to cause said clutch elements to rotate in unison with each other, and in which means is provided for rendering some of said friction elements inoperative. 125
11. In a slicing machine, the combination with a reciprocating carriage, of a rotatable knife adapted to slice substances on said carriage, manual means for actuating said carriage, a shaft, power means for actuating said shaft, a connection from said shaft to said knife, a clutch operatively connected to said shaft and to said manual means so that said knife may be operated from said manual means and said carriage from said power means through the intermediary of said clutch, a plurality of elements comprising said clutch, one of said elements being operatively connected to said manual means so as 130

- 150

- to rotate therewith and the other of said elements being operatively connected to said power means to rotate when said power means is actuated, a tapered recess in one of said elements, 5 a friction element arranged within said tapered recess between said elements and normally adapted to contact with both of said elements to cause said elements to rotate in unison with each other when one of said elements is rotated in one direction, a second tapered recess extending in the opposite direction to said first tapered recess and being formed in the same one of said elements as said first recess, a friction element in said second recess adapted to normally contact 10 with both of said clutch elements when the other of said clutch elements is rotated in the same direction, and means for rendering one of said friction elements inoperative so that the drive through said clutch by one of said driving means is rendered inoperative. 15
12. In a slicing machine, the combination with a carriage, of a rotating knife, power means for rotating said knife, manual means for reciprocating said table, a clutch arranged between the drive for said carriage and the drive for said knife comprising a plurality of rotatable elements, one of said elements being actuated by said manual means and the other of said elements being actuated by said power means, two sets of friction elements arranged between said clutch elements, one set of said friction elements being adapted to cause said clutch elements to rotate in unison with each other when one of said clutch elements is actuated by its driving means and the other set of said friction elements being adapted to cause said clutch elements to rotate in unison with each other when the other of said clutch elements is actuated, and means for rendering one of said friction elements inoperative to thereby disconnect the drive through 20 said clutch from one of said actuating means. 25
13. In a slicing machine, the combination with a carriage, of a rotating knife, power means for rotating said knife, manual means for reciprocating said table, a clutch arranged between the drive for said carriage and the drive for said knife comprising a plurality of rotatable elements, one of said elements being actuated by said manual means and the other of said elements being actuated by said power means, two sets of friction elements arranged between said clutch elements, one set of said friction elements being adapted to cause said clutch elements to rotate in unison with each other when one of 30 said clutch elements is actuated by its driving means, the other set of said friction elements being adapted to cause said clutch elements to rotate in unison with each other when the other of said clutch elements is actuated, and means for rendering one of said sets of friction elements inoperative to thereby disconnect the drive through 35 said clutch from one of said actuating means. 40
14. In a slicing machine, the combination with a reciprocating carriage, of a rotating knife, a shaft, a clutch on said shaft comprising a plurality of clutch elements, driving elements interposed between said clutch elements, one of which clutch elements is attached to said shaft and the other of which may be constrained to move with said first element by means of said driving element, operative connection between said second 45
- clutch element and said knife, a manual means for driving said shaft, power means for driving said shaft, and means for moving said driving element into inoperative position so as to render the drive to said knife through said clutch inoperative, said power means and said manual means being also operatively connected to said carriage to drive the same independently of said drive to said knife. 50
15. A device as claimed in claim 14 in which the driving means for causing said clutch elements to move in unison with each other comprises a friction roller interposed between said elements and being adapted to frictionally engage both of said elements when said first element is actuated and in which the means for rendering the said driving means inoperative comprises a pin for moving said friction roller out of normal operative position, and a cam for actuating said pin. 55
16. In a slicing machine, the combination with a slicing knife, of a carriage movable relative thereto, means for driving said carriage, means for rotating said knife independently of the drive to said carriage, a clutch for connecting said knife to said carriage driving means, a second clutch for connecting said carriage to said knife driving means, and means for selectively rendering said clutches inoperative comprising a single operating element, said clutches each 60 comprising a pair of elements rotatable relative to each other, means for causing said elements to rotate in unison with each other whenever either of said elements is actuated, and means for disconnecting the drive from one of said elements to the other without the necessity of disconnecting the drive from the other of said elements to the first of said elements. 65
17. In a slicing machine, the combination with a carriage, of a knife, means for manually reciprocating said carriage, power means for actuating said knife, a clutch for connecting said power means to said carriage so that said carriage may be driven by said power means, means for connecting said knife to said manual means 70 so that said knife may be actuated by said manual means, means for selectively rendering the drive to either said knife or said carriage from said power means inoperative, means for selectively connecting and disconnecting said manual means to said knife, and means for preventing the rotation of said power means by said manual means when said manual means is being actuated. 75
18. A slicing machine comprising a knife and carriage movable relative to each other, said knife being also mounted for rotative movement about its axis, mechanism for moving said knife and table relative to each other, mechanism for rotating said knife, two separate driving means, 80 and a clutch interposed between both of said mechanisms and each of said driving means comprising a plurality of elements rotatable relative to each other, a plurality of connecting elements arranged between said clutch elements, some of said connecting elements being operative to cause rotation of both of said elements in unison with each other when one of said elements is actuated in one direction while permitting free movement relative to each other in the opposite direction 85 and some of the others of said connecting elements being adapted to cause rotation of both of said clutch elements in unison with each other when the other of said clutch elements is rotated in the same direction as the first mentioned 90

- clutch element while permitting relative movement of said parts in the opposite direction, and means for rendering all of the connecting elements having the same identical purpose inoperative without destroying the operativeness of the remaining elements. 15
19. A slicing machine comprising a knife and carriage movable relative to each other, said knife being also mounted for rotative movement about its axis, mechanism for moving said knife and table relative to each other, mechanism for rotating said knife, two separate driving means, and a clutch interposed between both of said mechanisms and each of said driving means comprising a plurality of elements rotatable relative to each other, a plurality of connecting elements arranged between said clutch elements, some of said connecting elements being operative to cause rotation of both of said elements in unison with each other when one of said elements is actuated in one direction while permitting free movement relative to each other in the opposite direction and some of the others of said connecting elements being adapted to cause rotation of both of said clutch elements in unison with each other when the other of said clutch elements is rotated in the same direction as the first mentioned clutch element while permitting relative movement of said parts in the opposite direction, and means for rendering all of the connecting elements having the same identical purpose inoperative without destroying the operativeness of the remaining elements comprising a plurality of pins normally spring-pressed out of a position in which they will render said connecting elements inoperative, and a manually actuated cam member for moving said pins into a position to move said connecting elements into inoperative position. 35
20. A slicing machine comprising a knife and carriage movable relative to each other, said knife being also mounted for rotative movement about its axis, mechanism for rotating said knife, a rotatable hollow shaft operatively connected to said knife, a cam member slidable within said shaft, a clutch element secured to said shaft, a pin slidable in said clutch element, an inclined recess in said clutch element, a second clutch element rotatable relative to said first clutch element having a surface thereon opposed to said inclined surface of said recess, a friction element arranged between said clutch elements adapted to be wedged between said surfaces when one of said elements is rotated, a pin communicating with said recess and adapted to be engaged by said cam member so that when said cam member actuates said pin, said pin will move into said recess and prevent said friction element from wedging itself between said opposed surfaces thereby preventing the rotation of said clutch elements in unison with each other when one of said elements is rotated in the direction which normally causes said movement of said elements in unison, mechanisms for moving said knife and table relative to each other, and an operative connection from said clutch for driving said mechanism for driving said table and knife relative to each other, the disengaging of said friction element by said pin resulting in the disconnecting of the driving through said clutch to one of said mechanisms. 60
21. A device as claimed in claim 20 in which one of the clutch elements is provided with an additional recess similar to said first recess and in which said recess has a friction roller which is adapted to cause said clutch elements to rotate in unison with each other when said first friction roller is inoperative and the other of said elements is actuated in one direction. 65
22. In a slicing machine, the combination with a reciprocating carriage, of a rotatable knife adapted to slice substances on said carriage, manual means for actuating said carriage, a shaft, power means for actuating said shaft, a connection from said shaft to said knife, a clutch operatively connected to said shaft and to said manual means so that said knife may be operated from said manual means and said carriage from said power means through the intermediary of said clutch, a plurality of elements comprising said clutch, one of said elements being operatively connected to said manual means so as to rotate therewith and the other of said elements being operatively connected to said power means to rotate when said power means is actuated, a tapered recess in one of said elements, a friction element arranged within said tapered recess between said elements and normally adapted to contact with both of said elements to cause said elements to rotate in unison with each other when one of said elements is rotated in one direction, a second tapered recess in one of said elements, a friction element in said second recess adapted to normally contact with one of said clutch elements when the other of said clutch elements is rotated in the same direction, and means for rendering one of said friction elements inoperative so that the drive through said clutch by one of said driving means is rendered inoperative. 90
23. In a slicing machine, the combination with a rotatable slicing knife, of a carriage adapted to reciprocate past said knife, driving mechanism connecting said carriage and knife to cause them to move in unison with each other, a clutch in said driving mechanism, a plurality of means for actuating said driving mechanism operating through said clutch to cause said knife and carriage to move in unison with each other, and means for rendering said clutch inoperative for one of said actuating means only. 100
24. In a slicing machine, the combination with a rotatable slicing knife, of a carriage adapted to reciprocate relative thereto, a driving means for actuating said knife and carriage simultaneously, a second driving means for actuating said knife and carriage simultaneously, a clutch mechanism between said two driving means, said clutch mechanism including two cooperating elements one of which is adapted to be driven from one of said driving means and the other of which is driven from the other of said driving means whereby movement is imparted to said carriage and knife when either element is driven, operative engaging means between said clutch elements, and means for actuating said engaging means including means for rendering said clutch mechanism inoperative to impart reciprocation to said carriage when one of said driving means is being operated while maintaining the driving relation to said knife when the other of said driving means is being operated. 115
25. In a slicing machine, the combination with a reciprocating table, of a rotatable knife, manual means for driving said table, a clutch comprising a pair of relatively rotatable elements, oppositely acting groups of friction devices for operatively connecting said elements in driving relation with each other, one group of said elements being operative when one of said elements 125
- 140
- 145
- 150

is actuated by driving means, another of said groups being operative when the other of said elements is actuated by driving means, a driving connection between said first mentioned element and said knife, power means for actuating said last mentioned element, a driving connection between said manual means and said second mentioned element, whereby when both of said groups of friction devices are operative, the manual actuation of said table also actuates said knife through said clutch elements and also when said power means is actuated, said knife and table are driven through the intermediary of said clutch elements, and means for rendering said first mentioned group of friction devices inoperative so that the driving connection between said first mentioned element and said second mentioned element is destroyed, whereby said second mentioned element remains at rest and the drive to said table from said element through said manual means is inoperative without destroying the driving connection from said second element to said first element, whereby said manual means may be actuated to drive both said knife and table even though said power means is connected only in driving relation to said knife.

26. A slicing machine comprising a rotatable slicing knife, a carriage adapted to be moved rela-
